TOILET

Joseph G. Bruzenak, New Britain, Conn.

Application March 30, 1939, Serial No. 265,009

14 Claims.

(Cl. 4-10)

My invention relates to toilets.

It has among its objects to provide an improved flushing means for a toilet. A further object of my invention is to provide improved means adapted to provide a prolonged flow of flushing water while being adapted to use with an ordinary small diameter supply pipe and with an ordinary type of diaphragm operated flush valve and while also eliminating the need for other controlling mechanism and for the large tanks heretofore necessary. A still further object of my invention is to provide such improved means including an improved connection and arrangement of a plurality of tanks, whereby it is made possible to utilize air pressure in one of the tanks and thereafter gravity flow from said tanks, in such manner as thereby substantially to prolong the flow available for flushing while operating entirely under the control of the flush valve. Still other objects of my invention are to provide such an improved means which is especially adapted to use in connection with a toilet of the combined urinal and squat type described and claimed in my copending application Serial No. 235,010, and wherein my improved tanks are adapted to be disposed in an improved manner in the urinal member of such a toilet while supplying water for flushing the squat type toilet at the base thereof and being controlled by the flush valve adjacent this base. These and other objects and advantages of my improved construction will, however, hereinafter more fully appear.

In the accompanying drawing, I have shown for purposes of illustration one embodiment which my invention may assume in practice, the same, although not limited to use in connection therewith, being illustrated in connection with a toilet of the construction shown in my application mentioned.

In the drawing:

Figure 1 is a perspective view of such a toilet equipped with my improvements, certain portions being broken away and others shown in dotted lines to facilitate illustration, and

Fig. 2 is a simplified view of the flushing structure removed from the toilet, this structure being shown in somewhat diagrammatic form and partially in section, to facilitate illustration.

50 In this illustrative construction, the toilet is of the combined squat and urinal type comprising a base member 1 having a bowl 2 therein and a vertically grooved urinal member 3 upstanding from this base around the rear edge of the bowl 2; my improved flushing means, generally indi-

cated at 4 and hereinafter more fully described, being disposed within this member 3 and controlled by a usual flush valve 5 having a diaphragm 5a and operating handle 5b and disposed adjacent the base 1 at one side thereof, which valve 5 controls the flow of flushing water from a water line 6 through my improved means 4 to flushing outlets 7 disposed around the upper edge of the bowl 2.

Referring more particularly to my improved structure, it will be observed that in rear of the vertically grooved urinal surface 8 on the member 3, the latter member is hollow or chambered, as shown at 9, to provide ample space to receive the flushing mechanism 4, while permitting the member 3 to retain its customary general conformation. Further, due to the curved or grooved front face 8 thereon, it will be observed that the chamber 9 is of greater depth at its opposite sides than it is along its vertical center line, and that I have utilized this fact to enable me to dispose my improved flushing mechanism in an improved compact arrangement within the member 3 and thereby eliminate the necessity for any outside tanks.

Referring more particularly to the mechanism 4, it will be observed that the same includes tanks 10 and 11, herein disposed vertically in these portions of increased depth along opposite vertical sides and within the member 3. In a preferred construction, these tanks are of a relatively small diameter, in such manner as to enable them to be received within these spaces without increasing the depth of an charge in

out requiring any undue depth of or change in the member 3. As shown, the left-hand tank 4 is connected at its top to the water supply line 5 in any usual manner at a point within the member 3, and herein just beyond a flush pipe 12 which leads to a urinal flushing connection 13 at the top of the member 3. The other tank 11 is disposed parallel to the tank 10 and in the other enlargement of the member 3. Both tanks herein, as preferably, are also of the same diameter and length. If desired, they may be connected together at their top by a suitable transverse bracing connection, herein a rod 14. Further, it will be observed that they are connected at their bottom by a pipe 15, herein, as preferably, of larger diameter than the pipe 6 leading from the water main to the tank 10. Also, as illustrated, the tank 10 is connected at its bottom through a pipe 16, preferably of the same diameter as the pipe 15, to the flush valve 5, while the latter is connected to the flush connection 7 by a pipe 17, preferably of the same 55

diameter as the pipes 15 and 16. Thus it will be observed that while the inlet pipe 6 remains of usual small diameter, the pipes 16 and 17 on opposite sides of the diaphragm 5a of the 5 valve 5 are of equal diameter and both of larger diameter than the pipe 6.

In the use of this construction, it will be evident that when the valve 5 is closed, air will be 10 trapped in the top of the tank 11 in the space indicated at 18 and be under such pressure as is in the pipe 6, while the remainder of both tanks will be filled with water from this pipe 6. Consequently, when the valve 5 is opened, as, for example, by raising or lowering its operating handle 15 5b, a flow of flushing water will be established and maintained when the valve diaphragm 5a is opened, from both tanks 10 and 11 through the pipe 16 to the valve 5 and through the latter and the pipe 17 to the flushing connection 7. Further, 20 the water in the tank 11 will continue to be acted upon by the pressure built up in the top thereof until, as this tank is emptied, this pressure can no longer function, whereupon there will be a gravity flow from both tanks until both have 25 emptied as much as is possible due to the continued flow into the tank 10 through pipe 6. When, however, the valve 5 closes automatically, in the manner usual with such valves, the tanks will again fill, as shown in Figure 2.

30 As a result of my improved construction it is possible to obtain a flow of flushing water substantially in excess of that which would be delivered directly from a pipe 6 to a flush valve 5 and the outlet 7, while maintaining the piping, 35 including the pipe 6, of usual and inexpensive small diameter and the valve 5 open longer than has heretofore been possible. Also, it is made possible to obtain such a large flow while requiring only a small tank which can be conveniently disposed in locations not now possible, 40 as, for example, within a urinal as herein or between the studding of a building wall. In my improved construction, the additional water in the tank 11 is available and it is also made possible 45 to utilize the pressure of the air in the top 18 of this tank, in such manner as very effectively to prolong the flushing effect, as compared with previous constructions of which I am advised. Further, whereas it has heretofore been impractical 50 without a large tank to use such a valve with a pipe which leads therefrom to the flushing outlets, as, for example, the pipe 17, which is of larger diameter than the inlet pipe 6, in my improved construction, this difficulty has been overcome without requiring such a tank. Further, 55 it will be observed that my improved construction makes unnecessary the use of any float or any other control mechanism, in addition to the valve 5, while the tanks act to increase the flow and pressure to the latter valve in such manner as to enable the same to flush and then shut off satisfactorily, this being due to the prolonged pressure available to hold the valve 5 open for the necessary longer time.

60 65 While I have in this application specifically described one embodiment which my invention may assume in practice, it will be understood that this form of the same is shown for illustrative purposes and that the same may be modified and embodied in various other forms without departing from its spirit or the scope of the appended claims.

What I claim as new and desire to secure by Letters Patent is:

70 75 1. A toilet flushing mechanism having a water

inlet pipe and a larger outlet pipe leading to the toilet, a flush valve therebetween adapted to be controlled by water pressure acting thereon, and means for prolonging the pressure of water substantially free from air acting on said valve when opened to maintain said valve open for a longer period than is possible as a result of inlet flow.

2. A toilet flushing mechanism having a water inlet pipe and a larger outlet pipe leading to the toilet, a flush valve therebetween adapted to be controlled by water pressure acting thereon, and means including a supplementary pressure source built up by pressure in said inlet and receiving fluid from said inlet only after closure of said flush valve following flushing for maintaining 15 said valve open for a longer period whenever the same is opened.

3. A toilet flushing mechanism having a water inlet pipe and a larger outlet pipe leading to the toilet, a flush valve therebetween adapted to be controlled by water pressure acting thereon, and means including a supplementary pressure source built up by pressure in said inlet and a cooperating supplementary gravity supply for maintaining 20 said valve open for a longer period whenever 25 the same is opened, said means receiving fluid from said inlet only after closure of said flush valve following flushing.

4. A toilet flushing mechanism having a water inlet pipe and a larger outlet pipe leading to the toilet, a flush valve therebetween adapted to be controlled by water pressure acting thereon, and means including an operatively connected closed tank having a body of air sealed against escape to said outlet during repeated flushing and having 30 pressure therein built up by the inlet pressure for maintaining said valve open by the built up pressure for a longer period whenever said valve is 35 opened.

5. A toilet flushing mechanism having a water inlet pipe and a larger outlet pipe leading to the toilet, a flush valve therebetween adapted to be controlled by water pressure acting thereon, and means including an operatively connected closed tank having pressure therein built up by the inlet 40 pressure and a cooperating tank connected to said inlet and receiving fluid from said inlet only after closure of said flush valve following flushing for maintaining 45 said valve open by the built up pressure for a longer period whenever said valve is opened.

6. A toilet flushing mechanism having a water inlet pipe and a larger outlet pipe leading to the toilet, a flush valve therebetween adapted to be controlled by water pressure acting thereon, 55 and means including a tank connected to said inlet and to said valve and a supplementary tank connected to said tank and having pressure built up therein by the inlet pressure and receiving fluid from said inlet only after closure of said 60 flush valve following flushing for maintaining said valve open by said built up pressure for a longer period whenever said valve is opened.

7. A toilet flushing mechanism having a water inlet pipe and a larger outlet pipe leading to the toilet, a flush valve therebetween adapted to be controlled by water pressure acting thereon, and means including a tank connected to said inlet and to said valve and a supplementary tank 70 connected to said tank and having pressure built up therein by the inlet pressure, said last mentioned tank having a closed upper end forming a compression chamber for a body of air trapped therein and sealed by the water in said tanks 75

against escape to said outlet during repeated flushing.

8. In a toilet having a water supply and an outlet leading to said toilet, a flush valve between said supply and outlet, and a plurality of cooperating tanks, one connected to said inlet and both connected to each other and to said valve and said water supply being closed against entrance of extraneous air during flushing and said outlet receiving from said tanks a prolonged flow of water free from air during flushing.

9. In a toilet having a water supply and an outlet leading to said toilet, a flush valve between said supply and outlet, and a plurality of cooperating tanks, one connected to said inlet and both connected to each other and to said valve, said supply connection being connected to said first mentioned tank at the top thereof, and said tanks being connected to each other and to said valve adjacent the bottoms of said tanks.

10. In a toilet having a water supply and an outlet leading to said toilet, a flush valve between said supply and outlet, and a plurality of cooperating tanks, one connected to said inlet and both connected to each other and to said valve, said tanks being upright and connected only at their bottoms.

11. In a toilet having a water supply and an outlet leading to said toilet, a flush valve between said supply and outlet, and a plurality of cooperating tanks, one connected to said inlet

and both connected to each other and to said valve, said tanks being upright and disposed in spaced relation parallel to one another and having a connection therebetween of smaller cross section than said tanks.

12. In a combined urinal and squat type toilet, a base having a bowl, a urinal extending upward from said bowl, and flushing connections for said bowl including a plurality of operatively connected tanks disposed upright in said urinal.

13. In a combined urinal and squat type toilet, a base having a bowl, a urinal extending upward from said bowl, and flushing connections for said bowl including a plurality of operatively connected tanks disposed upright in said urinal, said urinal having a front urinal face and having hollow enlargements in rear thereof and along opposite edges thereof, and said tanks being disposed in said enlargements.

14. In a combined urinal and squat type toilet, a base having a bowl, a urinal extending upward from said bowl, and flushing connections for said bowl including a plurality of operatively connected tanks disposed upright in said urinal, said urinal having a front urinal face and having hollow enlargements in rear thereof and along opposite edges thereof each housing one of said tanks, and a flush valve controlling the flow from said tanks and disposed in front of said urinal adjacent said base.

JOSEPH G. BRUZENAK.
